DEVICE FOR HARMONIZING COLORS

Donald E. Rowe, Aurora, Ill., assignor to Kroehler Mfg. Co., Naperville, Ill., a corporation of Illinois

Application September 25, 1939, Serial No. 296,377

11 Claims. (Cl. 35—53)

This invention relates to a device for harmonizing colors and consists of the matters herein-after described and more particularly pointed out in the appended claims.

5 The device is primarily designed for use by merchants dealing in furniture, rugs, and other house fittings, where it is desired to exhibit to a customer various color combinations which may be displayed in pictured minature, as desired, on a board including a shadow box in which there is brought to appear in succession each of said color combinations. By the use of the device the customer is enabled to approximate a realization of the harmony of a color scheme, for example, in an actual room containing a furniture set, a rug, and walls, by the color scheme embodied in the pictured minature as displayed by the device.

20 The object of the invention is to provide a device of the kind which is of cheap and economical construction, which is readily and easily operated and which assures the display of many color combinations in exact accordance with the selection of the salesman or purchaser.

25 The advantages of the invention will appear more fully as I proceed with my specification.

In the drawings:

Figure 1 is a perspective view of the device.

30 Figure 2 is a side elevation of the same on an enlarged scale.

Figure 3 is a front elevation on the scale shown in Figure 2, with the base broken away.

35 Figure 4 is a front elevation of one of a series of transparencies which are embodied in the device, as will be later described and which presents in opaque color one of the several features, in this case a suite of furniture, the color of which is to be combined with other decorative features in a room.

40 Figure 5 is a side elevation of the device still further enlarged as compared to Figure 1, with the proximate side wall removed to disclose the inner structure.

45 Figure 6 is a view representing a vertical section through Figure 5 in a plane indicated by the line 6—6 of Figure 5.

Figure 7 is a partial section of Figure 6 in a plane indicated by the line 7—7 of Figure 6.

50 Figures 8, 9 and 10 are front elevations of three discs severally disposed, when assembled in the device, in the order of said figures upon a common central axis.

55 Figure 11 is a front disc shown on a larger scale than Figures 8, 9 and 10, which are on a much smaller scale.

Figure 12 is a fragmentary perspective view illustrating the disposal of said discs when brought to registry to present a color combination, as will be later described in the specification.

5 Referring now to that embodiment of the invention illustrated in the drawings: 15 indicates as a whole the improved device for harmonizing colors. 16 indicates a casing which encloses the operating parts of the device. This, as shown, is 10 provided with a top 17 of fanciful design and a base 18. The casing, as illustrated, is slightly inclined upwardly and backwardly so as to present a ready view of its face. 19 indicates the front wall of the casing and 20 indicates the back wall 15 (see Figure 5). Within the casing and intermediate the front and back walls 19 and 20 is a vertical frame 21, which is held rigidly within the casing by top and bottom cross bars 22, 22 and 23, 23 attached to the front and back walls 19 20 and 20 of the casing.

24 (see Figures 5, 6 and 7) indicates a wooden hub which is rotatable on a horizontal stud 25. Said stud is mounted in the frame 21 and in a diagonally disposed bar 26 fixed to spools 27, 27 25 secured to and projecting forwardly from the frame 21. 28 indicates a disc preferably made of a thin sheet of Masonite and having peripheral gear teeth 28^x. Said disc is fixed concentrically as by screws 29 to the front end of the 30 hub 24 (see Figure 7) with which it is rotative on the stud 25. The gear teeth 28^x of the disc 28 mesh with a shrouded pinion gear 30 located below it and fixed to a horizontal spindle 31 mounted at one end in the frame 21 as indicated 35 at 32 and within the front wall 19 of the casing in an upright bar 33 attached at its upper end to the spindle 26 and at its bottom end to a spool 34 projecting from the frame 21. The spindle 31 projects beyond said front wall 19 where it 40 has fixed to it a turn-button 35. By rotating the button 35 the shrouded pinion gear 30 is rotated and it in turn rotates the disc 28.

Within the frame 21 and extending parallel to the front wall 19 of the casing and to the 45 plane of the gear 28 is located a large disc 36 which is concentrically attached by screws 37 or otherwise to the rear end of the hub 24. Thus the disc 28 and the larger disc 36 will be rotated together by turning the turn-button 35. 50

Spaced back of the disc 36 and in planes parallel thereto are discs 38 and 39 which are fixed respectively on spacing bearing rings 38^a and 39^a (see Figure 7) which are independently rotative on the horizontal stud 25. The discs 38 and 39 55

have respectively peripheral gear teeth 38^x and 39^x . Mounted below on each side of the shrouded gear 30 on spindles 40 and 41 rotatively supported in the frame 21 and the front wall 19 of the casing are shrouded pinion gears 40^a and 41^a which are respectively engaged with the gear teeth 38^x and 39^x of the discs 38 and 39 . Turn-buttons 40^b and 41^b are fixed respectively to the spindles 40 and 41 beyond the casing wall 19 . The construction is such that the disc 38 may be rotated by the turn-button 40^b , and the disc 39 may be rotated by the turn-button 41^b .

The casing 16 is provided with an opening in which is fixed a shadow box 16^a as shown in Figures 1 and 3. Said box is disposed as shown above and to the right of the turn-button 35 which operates the disc 28 and its connected disc 36 . The horizontal mid-axis of said shadow box is in horizontal radial alignment with the central axis of the stud 25 on which the several discs 28 , 36 , 38 and 39 are mounted, as described above.

The disc 36 is provided with a plurality of equally, arcuately spaced openings 36^a spaced radially at like distances from the center of the disc and corresponding to the distance of the center of the shadow box 16^a from a point in horizontal alignment with the center of said disc. As shown, the several openings 36^a are rectangular and correspond in length and width with the length and width of the opening in said shadow box 16^a . Thus by turning the disc 36 , each of the openings 36^a may be brought into registry back of the shadow box 16^a .

The openings 36^a are covered by transparent sheets 36^b (see Figures 4 and 8). Upon each of said transparencies are depicted, by opaque color or other means, furniture pieces placed as in a room shown in perspective with two walls and a floor to view the furniture pieces to be arranged on said floor in proper relation to said walls. On the walls preferably, are depicted by opaque color or other means on said transparent sheet 36^b , any usual drapes, as curtains, with a mantle piece and a lamp disposed against the far wall. The divan and chair, as the main pieces, are colored in accordance with any primary selection, with which the colors of rug and walls are to be harmonized. In addition, other pieces of furniture, as shown in Figure 4 in the foreground without shading, may be blocked out with a color contrasting to or harmonizing with the two main pieces. Each opening 36^a is covered by a like transparency 36^b printed, colored or otherwise treated to present the same or other furniture pieces which are of different colors, there being in this case seven transparencies.

In the front wall of the casing above the turn-button 35 is an opening 16^b . The disc 28 is provided at points arcuately spaced at distances like the spacing of the openings 36^a in the disc 36 , with scales 28^a bearing indicia—one scale 28^a being correlated to each opening 36^a and adapted to register back of the opening 16^b in the front wall of the casing 16 when the transparency 36^b , presenting the furniture pieces colored to correspond to said indicia on the disc 28 , appears back of and in view through the shadow box 16^a of the casing. This is readily brought about by reason of the fact that the disc 28 and the disc 36 are fixed together and turn as one when the shrouded pinion gear 30 is operated by the turn-button 35 .

Said indicia on the disc 28 consists of the word "Furniture" or an abbreviation thereof, to-

gether with either the name of a color or abbreviation thereof, or of a number, preferably the latter, associated with said color on a chart 16^c which appears on the front wall of the casing below the opening 16^b headed by the word "Furniture." On said chart 16^c , in vertical succession, are printed the names of various colors—⁵ "Garnet," "Rose," "Rust," etc. Opposite each color is printed an associated numeral, as 1, 2, 3 and so on—in this case up to the number ¹⁰ 7 corresponding to the number of openings 36^a on the disc 36 . Below this chart is the turn-button 35 by means of which the disc 28 and the disc 36 are rotated to bring one of the openings 36^a into registry with the shadow box 16^a . ¹⁵

Below the turn-button 40^b appears the printed word "Wall," and below that a series of names of colors, as "Yellow," "Mauve," "Turquoise," and "Mocha," each associated with a number as ²⁰ 1, 2, 3, 4, and so on up to 7. These colors, as will appear later, are found on the disc 39 which bears at arcuately spaced intervals radially disposed patches of colors, severally corresponding with the colors named under the word "Wall" on the casing. ²⁵

Horizontally with the turn-button 40^b is the turn-button 41^b , below which appears the word "Rug." And below that is a chart 16^c in which appear the names of a series of colors—"Beige," "Rust," "Green," "Plum," and so on, each associated with a numeral 1, 2, 3, 4, and so on up to the numeral 7. ³⁰

The disc 38 is provided with arcuately spaced cut-outs 38^a , each presenting a part 38^b colored to correspond with one of the colors appearing in the chart 16^c as the color of a rug, said openings being adapted to be brought to registry back of the shadow box 16^a and to present the colored part 38^b in position back of the rug space defined in the transparency 36^b to be ⁴⁰ viewed through the transparency and to appear as a rug upon which the furniture is set. The disc 38 is operated by the turn-button 41^b to bring a rug of the required color to said position.

In like manner the wall color presented by ⁴⁵ the radial patches 39^a on the disc 39 are brought to registry, back of the disc 38 , with the shadow box 16^a , thus presenting to view through the transparency 36^b of the disc 36 a color to the part of the wall which is not blocked out by ⁵⁰ opaque paint or painting—first, by the furniture, drapes, mantle piece, and lamp presented by the disc; and, second, by the rug presented by the disc 38 —thus exhibiting the said color on the undecorated part of the wall. The relative positions of the discs 36 , 38 and 39 , when each is brought to registering position back of the shadow box 16^a , are illustrated in perspective in Figure 12. ⁵⁵

In addition to the word "Furniture" and a ⁶⁰ numeral associated with one of the colors under the word "Furniture" in the scale 16^c , the scales 28^a on the disc 28 bear the word "Rug" with the number associated with one of the numerals applied to a color in the scale 16^c , and the word "Wall" associated with a numeral in the scale 16^c corresponding to a color appearing in said scale. The scales 28^a including said three sets of indicia are within limits to appear back of the opening 16^b in the front of the casing. The ⁶⁵ indicia included in each scale 28^a present a suggested color combination in the furniture pieces, rug and walls as one to harmonize, in accordance with the best taste of the rug and furniture manufacturers. Thus when the cus- ⁷⁰ ⁷⁵ ⁸⁰ ⁸⁵ ⁹⁰ ⁹⁵

5 tomer, who generally has no idea as to an artistic color scheme, is first confronted with the device, he is asked as to his preferred color for the furniture pieces which he selects from the scale 16^c, whereupon the turn-button 35 is turned to bring the number on scale 16^c corresponding to that 10 color of furniture, to register back of the opening 16^b. At the same time the transparency 36^b bearing furniture of that color comes to 15 register back of the shadow box 16^a.

10 Below the number appearing on the disc 28 back of the opening 16^b there also appears the word "Rug" with a number corresponding to a 15 color of rug in scale 16^c, and a number corresponding to a color for the wall appearing in scale 16^d. By turning the button 41^b a rug of the color associated with the number appearing back of the opening 16^b is brought to registry back of the transparency 36^b. And by turning the 20 button 40^b the disc 39 is rotated to bring to registry with the shadow box 16^a a color patch 39^a which appears as the color of the wall.

25 Should the customer object to either rug or wall color and have a preference for other colors, various combinations of rug and wall may be tried by turning the buttons 41^b and/or 40^b to bring other colorings of rug and/or wall into the picture.

30 Should the customer want to try out other colors for the furniture pieces, the proper transparency 36^b together with the suggested colorings of rug and wall with the different color of furniture may be brought to view, and any combinations desired of the colors shown on the 35 several scales may be tried.

35 To assure the presentation of the intended transparency with the color of furniture as indicated in the scale 16^c and the proper color of rug and of wall as indicated respectively in the 40 scales 16^c and 16^d, each of the discs 36, 38 and 39 bear on the advancing side of the transparency 36^b of the rug piece 38^b and of the color patch 39^a, respectively, the numeral corresponding to the color associated therewith in their respective 45 scales on the front wall of the casing, as shown in Figures 8, 9 and 10. Thus in turning the buttons associated with the respective discs to rotate said discs to the right as indicated by arrows in Figures 6, 8, 9 and 10, the number associated 50 therewith in each case will appear first and the rotation must be arrested when the transparency 36^b, the rug piece 38^b and the color patch 39^a come to register back of the shadow box 16^a.

55 For brevity, the disc 36 which bears the features spaced in the direction of their movement and presenting the basic views in perspective, may be referred to as a basic member. And the discs 38 and/or 39 with similarly spaced features, which supplement the views presented by the basic member 36 in the final picture disclosed through the view opening, may be referred to as supplemental members—and this without any limitation as to the form or kind of movement of said members.

60 The operation of the device and its advantages for harmonizing colors will be readily understood from the foregoing description. By its use the salesman may come to an assured conclusion as to what the customer wants and what colors harmonize to suit the customer's taste. And the 65 customer may see and study the effect of different combinations of color as they will appear in a room at his home which, without such a device, he has heretofore been unable to visualize.

70 75 While in describing my invention I have re-

ferred to several details of construction and arrangement of parts, it will be obvious that they are capable of some modifications and changes without departing from the spirit of the invention which is not limited thereto except as 5 may be pointed out in the appended claims.

I claim as my invention:

1. In a device for harmonizing colors, a casing 10 provided with a view opening, a plurality of movable members, including a basic member and one or more supplemental members, disposed in succession back of said view opening, each provided with spaced features adapted to be brought to register with said view opening and being independently movable to that end, each feature of 15 said basic member being a transparency with a substantially opaque pictorial representation in perspective, each feature of the next succeeding supplemental member being a representation in perspective co-related to and adapted to be seen 20 through the non-opaque part of the basic member, and means for moving each movable member to bring one of its features to register with said view opening.

2. In a device for harmonizing colors, a casing 25 provided with a view opening, a plurality of movable members, including a basic member and one or more supplemental members, disposed in succession back of said view opening, each provided with spaced features adapted to be brought 30 to register with said view opening and being independently movable to that end, each feature of 35 said basic member being a transparency with a substantially opaque pictorial representation in perspective, each feature of the next succeeding supplemental member being a representation in perspective co-related to and adapted to be seen through the non-opaque part of the basic member, the feature of each movable member bearing a character to be correlated with said view 40 opening when it is brought to register therewith, and means for moving each movable member to bring one of its features to register with said view opening.

3. In a device for harmonizing colors, a casing 45 provided with a view opening, a plurality of movable members, including a basic member and one or more supplemental members, disposed in succession back of said view opening, each provided with spaced features adapted to be brought 50 to register with said view opening and being independently movable to that end, each feature of 55 said basic member being a transparency with a substantially opaque pictorial representation in perspective, each feature of the next succeeding supplemental member being a representation in perspective co-related to and adapted to be seen through the non-opaque part of the basic member, the features of each of the succeeding 60 movable members being pictorial representations which may be seen through the non-opaque parts of the members in front of it, and means for moving each movable member to bring one of its features to register with said view opening.

4. In a device for harmonizing colors, a casing 65 provided with a view opening, a plurality of movable members, including a basic member and one or more supplemental members, disposed in succession back of said view opening, each provided with spaced features adapted to be brought to 70 register with said view opening and being independently movable to that end, each feature of 75 said basic member being a transparency with a substantially opaque colored pictorial representation in perspective, each feature of the next

succeeding supplemental member being a colored representation in perspective co-related to and adapted to be seen through the non-opaque part of the basic member, an index member movable with said basic member provided with spaced scales of color combinations, each scale including a color for each movable member, said casing being provided with a second view opening associated with said color scales on said index member, a plurality of charts, one associated with each movable member and containing a list of colors severally indicating the colors of the spaced features on its associated movable member, and means for moving each movable member to bring its feature to register with said view opening.

5. In a device for harmonizing colors, a casing provided with a view opening, a plurality of movable members, including a basic member and 10 one or more supplemental members, disposed in succession back of said view opening, each provided with spaced features adapted to be brought to register with said view opening and being independently movable to that end, each feature 15 of said basic member being a transparency with a substantially opaque colored pictorial representation in perspective, each feature of the next succeeding supplemental member being a colored representation in perspective co-related to and adapted to be seen through the non-opaque part of the basic member, an index member movable with said basic member provided with spaced scales of color combinations, each scale including a color for each movable member, 20 said casing being provided with a second view opening associated with said color scales on said index member, a plurality of charts, one associated with each movable member and containing a list of colors severally indicating the colors of the spaced features on its associated movable member, the feature of each movable member bearing a character to be correlated with said view opening when it is brought to register therewith, and means for moving each movable member to bring its feature to register with said view opening.

6. In a device for harmonizing colors, a casing provided with a view opening, a plurality of rotatable discs, including a basic disc and one or 25 more supplemental discs, disposed in succession within the casing back of the plane of said view opening, each provided with spaced features adapted to be brought to register with said view opening and being independently rotatable to that end, each feature of said basic disc being a transparency with a substantially opaque pictorial representation in perspective, each feature of the next succeeding supplemental disc being a representation in perspective co-related to and 30 adapted to be seen through the non-opaque part of the basic disc, and means for rotating each disc to bring one of its features to register with said view opening.

7. In a device for harmonizing colors, a casing 35 provided with a view opening, a plurality of discs rotatable about a common axis, including a basic disc and one or more supplemental discs disposed in succession within the casing back of the plane of said view opening, each disc being provided with annularly spaced features adapted to be brought to register with said view opening and being independently rotatable to that end, each feature of said basic disc being a transparency with a substantially opaque pictorial representation in perspective, each feature 40 of the next succeeding supplemental disc being a colored representation in perspective co-related to and adapted to be seen through the non-opaque part of the basic disc, an index disc rotatable with said basic disc provided with annularly spaced scales of color combinations, each scale including a color for each rotatable disc.

8. In a device for harmonizing colors, a casing 45 provided with a view opening, a plurality of discs rotatable about a common axis, including a basic disc and one or more supplemental discs, disposed in succession within the casing back of the plane of said view opening, each disc being provided with annularly spaced features adapted to be brought to register with said view opening, and being independently rotatable to that end, each feature of said basic disc being a transparency with a substantially opaque pictorial representation in perspective, each feature 50 of the next succeeding supplemental disc being a representation in perspective co-related to and adapted to be seen through the non-opaque part of the basic disc, the features of each of the succeeding discs being pictorial representations which may be seen through the non-opaque parts of the discs in front of it, and means for rotating each disc to bring one of its features to register with said view opening.

9. In a device for harmonizing colors, a casing 55 provided with a view opening, a plurality of discs rotatable about a common axis, including a basic disc and one or more supplemental discs, disposed in succession within the casing back of the plane of said view opening, each disc being provided with annularly spaced features adapted to be brought to register with said view opening and being independently rotatable to that end, each feature of said basic disc being a transparency with a substantially opaque colored pictorial representation in perspective, each feature 60 of the next succeeding supplemental disc being a colored representation in perspective co-related to and adapted to be seen through the non-opaque part of the basic disc, an index disc rotatable with said basic disc provided with annularly spaced scales of color combinations, each scale including a color for each rotatable disc, said casing being provided with a second view opening associated with said color scales on said index disc, a plurality of charts, one associated with each disc and containing a list of colors severally indicating the colors of the spaced features on its associated disc, and means for rotating each disc to bring its feature to register with said 65 view opening.

10. In a device for harmonizing colors, a casing 70 provided with a view opening, a plurality of discs rotatable about a common axis, including a basic disc and one or more supplemental discs, disposed in succession within the casing back of the plane of said view opening, each disc being provided with annularly spaced features adapted to be brought to register with said view opening and being independently rotatable to that end, each feature of said basic disc being a transparency with a substantially opaque colored pictorial representation in perspective, each feature 75 of the next succeeding supplemental disc being a colored representation in perspective co-related to and adapted to be seen through the non-opaque part of the basic disc, an index disc rotatable with said basic disc provided with annularly spaced scales of color combinations, each scale including a color for each rotatable disc.

- said casing being provided with a second view opening associated with said color scales on said index disc, a plurality of charts, one associated with each disc and containing a list of colors 5 severally indicating the colors of the spaced features on its associated disc, the feature of each disc bearing a character to be correlated with said view opening when it is brought to register therewith, and means for rotating each disc to 10 bring its feature to register with said view opening.
11. In a device for harmonizing colors, a casing provided with a view opening, a plurality of discs rotatable about a common axis, including a 15 basic disc and one or more supplemental discs, disposed in succession within the casing back of the plane of said view opening, each disc being provided with annularly spaced features adapted to be brought to register with said view opening 20 and being independently rotatable to that end, each feature of said basic disc being a transparency with a substantially opaque colored
- pictorial representation in perspective, each feature of the next succeeding supplemental disc being a colored representation in perspective correlated to and adapted to be seen through the non-opaque part of the basic disc, an index disc 5 rotatable with said basic disc provided with an annularly spaced scales of color combinations, each scale including a color for each disc, said casing being provided with a second view opening associated with said color scales on said index disc, 10 a plurality of charts on said casing, one associated with each disc and containing a list of colors severally indicating the colors of the spaced features on its associated disc, turn-buttons on said casing, one for each disc, each turn-button being associated with the chart indicating the colors of the features of that disc, and means intermediate said several buttons and their associated discs for rotating the same to bring its features to register with said view opening. 20

DONALD E. ROWE.
